UNITED STATES PATENT OFFICE

139,785

DESIGN FOR A DRESS

Eleanor K. Graham, New York, N. Y.

Application November 21, 1944, Serial No. 116,462

Term of patent 3½ years

(Cl. D3—26)

To all whom it may concern:

Be it known that I, Eleanor K. Graham, a citizen of the United States, residing in New York city, in the county of New York and State of New York, have invented a new, original, and ornamental Design for a Dress, of which the following is a specification, reference being had to the accompanying drawing, forming part thereof.

Figure 3 is an enlarged fragmentary front view of the skirt portion of the dress shown in Figure 1, illustrating the closure means in an open position.

I claim:

The ornamental design for a dress, substantially as shown.

ELEANOR K. GRAHAM.
